(57) **CLAIM**

We claim the ornamental design for part of a vacuum cleaner, as shown and described.

DESCRIPTION

FIG. 1 is a perspective view of part of a vacuum cleaner showing our new design;

FIG. 2 is a side view thereof;

FIG. 3 is side view of the opposite side of FIG. 2;

FIG. 4 is a front view thereof;

FIG. 5 is a rear view thereof;

FIG. 6 is a top view thereof; and,

FIG. 7 is a bottom view thereof.

The broken lines shown in the drawings illustrate portions of part of a vacuum cleaner that form no part of the claimed design.
